Inventor.

Benjamin F. Williams.

UNITED STATES PATENT OFFICE.

BENJIMAN FRANKLIN WILLIAMS, OF NORWOOD, COLORADO.

SICKLE-HEAD.

SPECIFICATION forming part of Letters Patent No. 637,951, dated November 28, 1899.

Application filed January 20, 1899. Serial No. 702,859. (No model.)

To all whom it may concern:

Be it known that I, BENJIMAN FRANKLIN WILLIAMS, a citizen of the United States, residing at Norwood, in the county of San Miguel and State of Colorado, have invented a new and useful Improvement in Sickle-Heads for Mowing-Machines, of which the following is a specification.

My invention relates to improvements in sickle-heads in which an oscillating shuttle working in a plate connected to the sickle constitutes the framework of the invention.

The object of my invention is to provide a sickle-head which will allow the sickle to be adjusted to the cutting of any variety of grass without creating the strain incident to other kinds of sickle-head connections on the pitman and crank-wheel. I attain this object by the mechanism illustrated in the accompanying drawings, in which—

Figure 1 is a vertical section of the entire invention; Fig. 2, a top view of the entire invention.

Similar letters refer to similar parts throughout both views.

The plate *d*, connected to the sickle by the rivets *f*, constitutes the framework of the invention. In the plate *d* works the shuttle *c*, working on hardened-steel bearings at the points *e*. The shuttle *c* is composed of the finest machine-steel, tempered so as to render it as resistible as possible to the friction of the bearings.

The bearings *p e* are formed by the set-

screw *b* extending through the plate *d* on the 35 rear end and a piece of steel welded into the plate *d* on the front end.

The set-screw *b* screws through the plate *d* and makes it possible to regulate the tightness of the shuttle *c* against the bearings *p e*. 40 A safety-tap is attached to render it more secure.

The set-screw *b* is composed of a very high grade of machine-steel.

The plate *d* is composed of Norway iron. 45 I am aware that pitman *a* has been used with the style of connection shown in the drawings and fastened in different ways, and therefore I do not claim any invention on pitman; but

What I do claim as my invention, and desire to secure by Letters Patent, is—

In a sickle-head joint, a rigid member firmly secured to the sickle-bar, two projections on said rigid member, one of said projections 55 having a rigid pivot extending therefrom, an adjustable pivot extending from the second projection, a movable member supported by these pivots, and having two pivots extending from the sides at right angles to the 60 line of suspension, a pitman, and two plates secured to the sides of said pitman and adjustably engaging the pivot-points of the movable member, substantially as described.

BENJIMAN FRANKLIN WILLIAMS,

Witnesses:

E. E. RAINES,

DAVID WILLIAMS.
